UNITED STATES PATENT OFFICE

147,475

DESIGN FOR A FRAME FOR EYEGLASSES

Morris Schwartz, Sunnyside, N. Y.

Application January 14, 1947, Serial No. 136,133

Term of patent 3½ years

(Cl. D57—1)

To all whom it may concern:

Be it known that I, Morris Schwartz, a citizen of the United States, residing at Sunnyside, County of Queens and State of New York, have invented a new, original, and ornamental Design for Frame for Eyeglasses, of which the following is a specification, reference being had to the accompanying drawing, forming part thereof.

Fig. 1 is a front elevational view of a frame for eyeglasses, showing my new design;

Fig. 2 is a side elevational view thereof.

The characteristic features of my design reside in the bowlike ornamentation on the bridge in combination with the winglike formations at the outer ends of the frame.

I claim:

The ornamental design for a frame for eyeglasses, as shown and described.

MORRIS SCHWARTZ.
